PHOTOELECTRIC TUBE AND METHOD OF
MANUFACTURE

Gerhard Lewin, Maplewood, and John Benes, Jr.,
Geneva, Ill., assignors to Continental Electric
Company, Geneva, Ill., a corporation of Dela-
ware

Application April 22, 1947, Serial No. 743,040

6 Claims. (Cl. 250—165)

1

This invention relates to improvements in photo-electric tube and method of manufacture and to the process of making such tubes, especially for the production of very small tubes.

In the manufacture of very small phototubes, such for instance, as of a size of approximately one inch in length and three-sixteenths inch in diameter, the size of the envelope does not admit of as much mounting structure as is provided ordinarily in larger phototubes. Moreover, the cathode is so close to the surrounding envelope as to cause danger of over-heating of the cathode in forming the press and sealing-in operations.

One object of this invention is to improve the construction of the tube, particularly the mounting of the cathode, whereby it may be supported, if desired, in part at least by the wall of the envelope, requiring only a single connection therewith which forms the lead, and is located at the center of the lower end of the cathode. The cathode is formed of very thin sheet-metal having sufficient resiliency so that its sides expand laterally against the walls of the envelope and, therefore, will be supported by the envelope without more than the single connection or lead.

A further object of the invention is to produce a phototube as small as possible, and at the same time to avoid over-heating of the cathode. A considerable amount of heating is required to form the press, much more than for the sealing of the exhaust tubing onto the glass envelope of the tube. A glass that does not contain lead, such as lime glass, is used to form the envelope, whereas a lead glass of much lower melting point may be used to form the exhaust tubing, to be sealed to the envelope by a lower heating operation. The press is formed also of a glass which does not contain a lead oxide, and is formed before the elements are assembled in the envelope.

One embodiment of the invention is illustrated in the accompanying drawings in which:

Fig. 1 is a side elevation of a phototube and exhaust tube sealed together;

Fig. 2 is a side elevation of the phototube after sealing thereof;

Fig. 3 is a cross-section therethrough on the line 3—3 of Fig. 2.

The invention is shown as applied in a phototube of minute size which is, however, exaggerated in the drawings for clearness of illustration. This phototube may be of a size, for instance, of about one inch in length and three-sixteenths inch in diameter, which size, however, is mentioned only as an example.

The phototube illustrated comprises a glass

2

envelope 1, within which is mounted the usual cathode 2 and anode 3. The getter pill is illustrated at 4 and is shown as mounted on the anode 3, merely for purpose of illustration; it may be mounted in any convenient position within the envelope.

The leads for the elements 2 and 3 are shown at 5 and 6, respectively, both sealed within a stem or press 7. Also sealed in the stem or press 10 are pins 11 connected at one end with the leads 5 and 6 and projecting at the opposite end from the stem or press to be engaged in a socket or other connector for the cell, supporting the cell thereby.

15 Due to the minute size of the envelope 1, the cathode 2 is mounted in an improved manner without requiring the several supports ordinarily provided heretofore. In this form of the invention, the cathode 2 is formed of sheet-metal 20 coated in the usual manner to provide a photo-emissive cathode surface, and has sufficient resiliency so that it may be curved between opposite sides of the envelope 1, as shown in Fig. 3, and will be supported and retained by the walls 25 of the envelope without requiring the usual auxiliary supports. Thus only a single connection is needed, the attachment of the lead 5 thereto, and yet the cathode will be retained effectively in place. This type of mounting is particularly 30 important in a minute tube. While the cathode may expand uniformly throughout a semi-cylindrical portion of the envelope, and bear thereagainst about its periphery, it is shown as having flaring sides 12 bearing thereagainst only at 35 opposite sides of the envelope.

To avoid darkening of the envelope in the flashing of the caesium in the pill 4, the envelope is formed ordinarily of a glass which does not contain lead oxide because the lead oxide would be reduced by the caesium and cause a darkening effect on the envelope. We have found that this difficulty can be overcome if the envelope 1 is made of lime glass, as the material now available for this purpose without the use of lead oxide glass.

40 The press 7 is formed with the leads 5 and 6 inserted therein, before the cathode 2 is mounted thereon. The cathode 2 and the anode 3 and pill 4 are heat-sensitive, and are mounted in the tube 1 in any suitable manner that will not affect the use thereof, after the press 7 is made. The press is integral with the envelope 1, and likewise, must 45 not contain lead oxide.

An exhaust tubulation is shown at 8, which initially has a flared end 9, capable of being

sealed directly to the end of the envelope 1. This tubulation 8 may be formed of lead glass with its relatively low softening point since there would be no tendency for a darkening of the wall of the envelope from the tubulation itself. Thus less heat is required due to the relatively soft character of the exhaust tubulation, to seal the flared end 9 thereof, to the envelope 1. The glass envelope is not appreciably softened by this sealing action and the heating of the latter is just sufficient to soften the lead glass tubulation.

After the tubulation 8 is sealed to the envelope, the tube is exhausted in the usual manner, and then the end is sealed as indicated at 10, by sealing the inner end of the tubulation 8 in the manner indicated in dotted lines in Fig. 1, and in Fig. 2.

In this way, the danger of over-heating of the cathode is avoided, and also the darkening of the envelope. At the same time, the construction permits the manufacture of the tube in a minute size in a practical manner.

While the invention is illustrated in one embodiment thereof, as described above, it will be understood that it should not be restricted to this embodiment but that changes may be made in the construction without departing from the invention, except as specified in the claims.

We claim:

1. A phototube comprising an enclosed envelope having a surrounding wall, an anode and cathode mounted in the envelope and each having a lead connected therewith, said cathode including a self-sustaining sheet of material connected with the lead thereof at one end intermediate the width of said sheet, and having flaring sides bearing against substantially opposite sides of the wall of the envelope and supported thereby in bridging relation between said opposite sides.

2. A process of forming a phototube with a glass envelope having a projecting integral stem portion at one end thereof, comprising enclosing leads in said stem portion and applying heat and pressure thereto to seal the leads therein in position with the stem projecting outwardly from the end of the envelope, inserting light sensitive elements within the envelope and connecting them with the leads, sealing an exhaust tubulation to the opposite end of the envelope, exhausting the envelope therethrough, and sealing off the envelope at the inner end of the tubulation.

3. A process of forming a phototube with a glass envelope having a projecting integral stem portion at one end thereof, comprising enclosing leads in said stem portion and applying heat and

pressure thereto to seal the leads therein in position with the stem projecting outwardly from the end of the envelope, inserting photo-electric elements within the envelope and connecting them with the leads, sealing an exhaust tubulation to the opposite end of the envelope, exhausting the envelope therethrough, and sealing off the envelope at the inner end of the tubulation.

4. A process of forming a light sensitive tube 10 with an envelope having a press at one end thereof, comprising enclosing leads in said press, inserting light sensitive elements within the envelope and connecting them with the leads, sealing an exhaust tubulation to the opposite 15 end of the envelope, exhausting the envelope therethrough, and sealing off the envelope at the inner end of the tubulation.

5. A process of forming a light sensitive tube with an envelope having a press at one end 20 thereof, comprising enclosing leads in said press, inserting photo-electric elements within the envelope and connecting them with the leads, applying an exhaust tubulation having a flaring inner end to the outer end of the envelope with 25 the flaring end closing said end of the envelope, sealing said flaring end to said end of the envelope, exhausting the envelope therethrough, and sealing off the envelope at the inner end of the tubulation outwardly of the flaring end 30 thereof.

6. A process of forming an electric discharge tube with an envelope having a press at one end thereof, comprising enclosing leads in said press, inserting electric discharge elements within the 35 envelope and connecting them with the leads, sealing an exhaust tubulation to the opposite end of the envelope, exhausting the envelope therethrough, and sealing off the envelope at the inner end of the tubulation.
